UNITED STATES PATENT OFFICE.

JOHN BELMER ARMSTRONG, OF GUELPH, ONTARIO, CANADA.

CARRIAGE-GEAR.

SPECIFICATION forming part of Letters Patent No. 319,378, dated June 2, 1885.

Application filed October 18, 1884. (No model.) Patented in Canada September 4, 1884, No. 20,131.

To all whom it may concern:

Be it known that I, JOHN BELMER ARMSTRONG, a subject of the Queen of Great Britain, residing at Guelph, in the county of Wellington, Province of Ontario, Canada, have invented certain new and useful Improvements in Carriages; and I hereby declare the following to be a full, clear, and exact description of the same, reference being had to the accompanying drawings, forming a part of the same, wherein—

Figure 1 is a general perspective view of a running-gear embodying my invention. Fig. 2 is a view of one of the side springs, its curved or C-shaped supports and perch, showing relative shape of side to points of suspension and the self-compensating position they assume when heavily laden. Figs. 3 and 4 are details of shaft-shackles, anti-rattler springs, front axle, and connections to axle. Figs. 5, 6, and 7 are details showing the formation of clips, ends of body-loops, and their connections to the side springs. Fig. 8 is a rear view of a phaeton-body, showing the construction of the front and rear body-loops in hanging the body and the manner of attaching the cross-straps. Figs. 9 and 10 are views of the rubber cushion and the clip for securing the same.

Like letters refer to like parts wherever they occur.

The object of my present invention is to produce a light, graceful, and serviceable side-spring steel running-gear for vehicles; and it consists, generally, in various novel details of construction, all as will hereinafter more fully appear.

The main or prominent features are, first, the upward and inward extension of the spring-perches to form spring-supports integral with the perches, to which are shackled the cyma-reversa single-plate side springs, whereby the construction is simplified, and strength combined with lightness is obtained with decreased number of parts; and, secondly, the attaching of the body-loops directly to the sidesprings on opposite sides of the transverse center and substantially equidistant from each other and from the ends, whereby the intermediate spring-bar is dispensed with, the strain along the springs is equalized, the freedom of the spring between the spring-bar is

insured, liability to fracture of the spring is reduced, teetering motion of the body after passing obstructions is avoided, and the body sits 55 much lower than in the previous constructions. There are minor but material features which will be more fully pointed out in the subsequent description.

I will now proceed to describe my invention more fully, so that others skilled in the art to which it appertains may apply the same.

In the drawings, A indicates the front axle, on which is pivoted, by means of a spring-clevis, D, suitable wearing-plates, and king-bolt, a steel head-plate, C, having upward-curved arms or ends which support the perch.

B indicates the rear axle, and E spring steel-plate perches, which extend from the head-plate to the rear axle, and are curved 70 upward and inward into general C form at the extremities to form spring-supports F integral with the perches E.

G indicates steel side springs of single plate, tapered in thickness at the extremities, of 75 cyma-reversa form or double curvature, and suspended at the extremities from the C-curves F of the perches E by free swinging shackles.

H and I indicate body-loops, which are 80 clipped directly to the cyma-reversa side springs, G, and I is one of the draw-jacks secured to the front axle.

The several parts and their general relation each to the other having been indicated above, 85 the special features of each and the advantages thereof will next be pointed out.

It will be noticed that the ends of the body-loops H I are directly connected to the side springs, G, on each side of the centers, instead 90 of being supported, as usual, on spring-bars resting above and on the centers. The distance between the body-loops is about one-third the total length of the side springs. As will be seen, this method of connection has various advantages, some of which are as follows: First, it does away with top leverage and twisting of connections, as the end fastenings of the body-loops are about level with the points of suspension on the ends of the side 95 springs; second, the strain is more equalized along the plates, and they are rendered less liable to breakage. It also prevents a teetering or continued motion after passing over

obstructions, which was the case in this class of vehicle when the weight rested on the centers. It also looks neater, is lighter, and allows the body to sit low without undue drop-
ping of the suspension-loops.

The things to be desired in a carriage-spring are ease of motion and lightness combined with sustaining capacity. In side springs as usually formed from laminated plates and sus-
pended on swinging shackles the main plate is of equal thickness its entire length between the eyes, usually from a quarter to five-sixteenths of an inch. The result of this shape and thickness of plates is, that in several inches of the spring ends close to the eyes there is very little or any elasticity, which is so much stock and length of spring wasted, and has to be provided for in that much extra weight of spring between those points, as the rigid parts act as so much leverage on the center, making or causing the elasticity to be in that direction. I have obviated these faults and obtained the desired results by a peculiar shaping and making the ends quite light, which will be better understood by reference to Fig. 2 and dotted lines K.

It will be noticed that the ends of the plate are so formed as to assume an upwardly-curved shape, forming steel spring suspension-
straps toward the stiffer parts of the spring. Of course when the ends assume this position the strain on these parts is to a great extent of a tensile nature, thus getting the entire benefit of the length and weight of the spring.

It will be further seen that when strained or heavy laden the cyma-reversa side springs touch, and are supported on the perches at or near the ends of the same, where, when wished for, they are met by the cushions *m*, of rubber or other suitable material, to prevent noise and chafing. Some of the results of this peculiar shaping and the spring-plates being made quite thin and flexible toward the ends are, very easy motion with light or heavy loads, and when very heavily laden the spring receives the additional sustaining or compensating capacity in the ways shown.

It will be noticed that the flat steel-plate perches *E* are extended upward in a C or curved shape, *F*, to form supports for the side springs. On the ends of these curved supports are eyes to support the swinging spring-shackles. The eyes formed on the ends of these supports are placed in a proper position above the perches to correspond with the compensating action of the side springs, as previously described, and they may also be made practically rigid, if wished for. The rubber cushion, which is shown as a flanged hemi-
sphere, *m*, is fastened to the perches by a wrought-metal strap, *r*, having a hole in the center, through which the rubber projects, and the strap is clinched on the lower side of the perch. (See Fig. 10.) As most of the weight in nearly all carriages is back of the center, tending to make the body set lower behind, I obviate this tendency by placing the body-

loops slightly nearer the rear ends of the side springs, and also make those ends proportionately heavier, thus causing the carriage to ride level when loaded.

Figs. 3 and 4 show the connection of the draw-jacks *I* and anti-shaft-rattler springs to the naked axle, in which any lateral motion of the jack is prevented by the pin *g*, which is recessed into the axle. The draw-jacks and the anti-shaft-rattlers are then secured by the bolts *o*, which are screwed into the extended ends of the draw-jack, forming a rigid and substantial connection, as described. I preferably set the draw-jack on top of the axle; but it can also be secured in a similar way to the front, back, or bottom of the axle.

The method of connecting the body-loop ends to the side springs is shown in Figs. 5, 6, and 7, Fig. 5 being a sectional view. Fig. 6 is a perspective view of the connecting-clip over the side springs, made from round steel, the cross-bar of which has a flat bottom with a raised seat, *i*, in the center, which is recessed into the spring. The inside corners of these clips are rounding to fit the edges of the spring-plate, and the outside corners, being square, give the clip great strength at those points where it is required. It will also be noticed the holes in the body-loop ends, through which the clip ends pass, (see Fig. 7,) are re-enforced by projecting bosses *j*, the inside corners of which are also rounded out to fit the edges of spring *G*, thus forming an efficient and neat connection in all its parts.

Referring now to Fig. 8, it will be noticed that the front loop, *l*, is turned downward and the back loop, *H*, upward at the outer ends, to suit the side conformation of a phaeton or any crooked body; but these loops can be adjusted to suit all kinds of carriage-bodies, thus forming a very neat and cheap method of hanging up this class of body, which is usually an expensive job.

The cross-straps *J*, which are usually attached to phaetons for appearance, in this case are made useful also. The upper ends are secured to the body in the usual way; but the lower ends of the cross-straps are attached to the ends of the bolts *k*, which hold the spring-shackle hangers in position, thereby tending to prevent undue swinging or sinking of the body on the side which is heavy laden, and also giving the rear of the carriage a fine and finished appearance.

I am aware that it is not new to use a tapered single-plate C-spring with flexible connections to support a side spring, and make no claim to such construction.

Having thus described the nature and advantages of my invention, what I claim, and desire to secure by Letters Patent, is—

1. In a buggy or carriage gear, the combination of spring-perch plates having inwardly-curved C-supports integral therewith and cyma-reversa single-plate side springs, substantially as and for the purposes specified.
2. In a buggy or carriage gear, the combi-

nation of **C**-spring supports, cyma-reversa side springs, and body-loops attached directly to the cyma-reversa single-plate side springs on opposite sides of the transverse center, substantially as and for the purposes specified.

3. In a buggy or carriage gear, the combination of **C**-spring supports, cyma-reversa single-plate side springs, and body-loops attached directly to the side springs at substantially equal distances from each other and from the ends of the spring.

4. The combination of a flanged rubber cushion and wrought-metal cushion-clip having a central hole and strap ends, substantially as and for the purposes specified.

5. In vehicle-gear, the combination, with the side spring having a recess or depression, of a clip having inside rounded corners, and a seat or projection on the cross-piece, and a body-loop having projecting annular bosses cut away 20 on the adjacent or spring faces, substantially as and for the purposes specified.

In testimony whereof I affix my signature, in presence of two witnesses, this 11th day of October, 1884.

JOHN BELMER ARMSTRONG.
